UNITED STATES PATENT OFFICE.

JOHN A. ROBERTSON, OF ROCHESTER, NEW YORK, ASSIGNOR TO EASTMAN KODAK COMPANY, OF ROCHESTER, NEW YORK, A CORPORATION OF NEW YORK.

PHOTOGRAPHIC-PRINT WASHER.

1,053,223.

Specification of Letters Patent. Patented Feb. 18, 1913.

Application filed October 21, 1911. Serial No. 655,926.

To all whom it may concern:

Be it known that I, JOHN A. ROBERTSON, of Rochester, in the county of Monroe and State of New York, have invented certain 5 new and useful Improvements in Photographic-Print Washers; and I do hereby declare the following to be a full, clear, and exact description of the same, reference being had to the accompanying drawings, 10 forming a part of this specification, and to the reference-numerals marked thereon.

My present invention relates to photography and more particularly to photographic printing, and it has for its object to 15 provide a simple and efficient device for washing the prints after they have been passed through the various developing and fixing solutions.

The improvements are directed in part toward providing arrangements whereby the prints are constantly subjected to a fresh 20 stream of water and are kept moving, being prevented from lodging at any one point and from clogging either the incoming or 25 outgoing stream.

To these and other ends the invention consists in certain improvements and combinations of parts all as will be hereinafter more fully described, the novel features being 30 pointed out in the claims at the end of the specification.

In the drawings: Figure 1 is a top plan view of a print washer constructed in accordance with and illustrating one embodiment of my invention; Fig. 2 is a transverse vertical section taken substantially on the line 2—2 of Fig. 1; Fig. 3 is a detail section, enlarged, of the discharge nozzle, taken substantially on the line 3—3 of Fig. 1, and Fig. 40 4 is a detail section taken substantially on the line 4—4 of Fig. 3.

Similar reference numerals throughout the several figures indicate the same parts.

Referring more particularly to the drawings, 1 indicates a container that may be conveniently formed of sheet metal to comprise two substantially semi-cylindrical treating chambers 2 and 3 lying adjacent to and extending parallel with each other.

The inner or adjacent walls 4 thereof merge 50 into one which forms a central wall or partition extending the length of the container, and the top of which is considerably below the edges of the outer walls 5 and 6 and below the water level of both chambers, as 55 hereinafter defined.

A discharge nozzle, preferably composed of a pair of parallel pipes 7, separated to the extent of the thickness of the center wall 4 and each having a series of perforations 8 60 in its under side, is preferably removably supported on the top of the wall 4. To this end the latter may be fitted with transversely extending chairs 9 having seats 10 therein on which the pipes 7 rest, and the latter are 65 preferably connected at a central point by a coupling 11 having a nipple 12 to which a flexible or other pipe 13 connected to a faucet or other source of fluid supply, is joined. 70

The perforations 8 in the nozzle lie close to and above the inner walls 4 of the chambers 2 and 3 and when water under pressure is introduced into the nozzle, a stream is directed downwardly along these walls in each 75 case and is thence directed outwardly and upwardly, as indicated by the arrows in Fig. 2, so that circular currents are set up in the chamber due to the curvature of the walls. I have further found by experiment that in 80 order to obtain an efficient circulation and a complete circular movement of these currents it is preferable that the inner wall 4 of the chamber at approximately the point where it merges into the bottom wall be of 85 a less degree of curvature than the corresponding portion of the outer or opposite walls 5 and 6, substantially in the ratio shown.

The prints to be treated are simply thrown 90 into the chambers whereupon they revolve about in the constantly freshened bodies of water, being turned over and over in the process and prevented from adhering either to each other or to the walls of the container. 95

Inasmuch as a pocket of dead water is apt to form in the neighborhood of and

above the discharge point of the nozzle where the stream or current after completing the circuit has about lost its momentum, and hence the prints are likely to come to rest and lodge at this point, I provide in each chamber a downwardly curved baffle plate 14 that presents a continuous concave baffle surface extending from a point above the surface level of the chamber down to a spaced relationship with the top of the center wall 4, which baffle plate preferably extends throughout the length of the receptacle and of the nozzle pipes 7. They thus form between them a chamber 15 that constitutes an overflow chamber and is provided with an overflow opening 16 at one end, or if desired, both ends of the container. The discharge nozzle 7 is located in this chamber and discharges through passages 17 formed between the baffle plates 14 and the center walls 4.

The baffle plates, aside from forming the overflow chamber, tend to direct the spent current crossing the chambers at the surface downwardly again and offer a smooth wall against which the prints are not disposed to lodge. Furthermore, the passages 17, which form the only communication between the respective treating chambers 2 and 3 and the overflow chamber 15 must afford a means of exit for the returning currents on their way to the point of discharge, even though the nozzle is discharging through the same passages. The water that has made the circuit of each chamber and arrived in the vicinity of the baffle plate, as before mentioned, is thus accelerated in its movement as it is drawn beneath the lower edge of the latter into the overflow chamber. In this way the two currents, the one incoming and the other outgoing, pass very close to each other and if any of the prints are carried to the point of egress from the treating chambers 2 and 3, they are immediately taken up by the stronger, or at least more concentrated incoming currents and are again started on their revolutions, as before. Thus the frequent trouble heretofore had with many devices of the kind due to the prints clogging, eventually, where the water runs off from the chamber, is obviated. The passages 17 and the discharge points of the nozzle are all well below the normal surface level of the water in all the compartments, as defined by the overflow opening 16, and I have found that the degree of submergence of the nozzle has quite a little to do with the efficiency and strength of the currents produced, but the proportions illustrated, I believe to be about right.

I claim as my invention:

1. In a photographic print washer, the combination with a chamber of substantially semi-circular cross section, of means for di-

recting a stream downwardly along one side wall of the chamber, the curvature of said side wall where it merges with the bottom wall being less than the curvature of the corresponding portion of the opposite wall.

2. In a photographic print washer, the combination with a treating chamber and an overflow chamber, said chambers being provided with an intercommunicating substantially vertical passage below the overflow level of the overflow chamber and above its bottom, of means for directing a stream from said passage downwardly into the treating chamber.

3. In a photographic print washer, the combination with a treating chamber and an overflow chamber, said chambers being provided with an intercommunicating substantially vertical passage below the overflow level of the overflow chamber and above its bottom, of a discharge nozzle arranged in the overflow chamber to direct a stream downwardly through the passage into the treating chamber.

4. In a photographic print washer, the combination with a substantially semi-cylindrical treating chamber, of a nozzle arranged to extend continuously along one of the side walls of the chamber and to discharge a stream from a point well below the normal surface level of the chamber downwardly along said wall and a baffle member arranged to provide a continuous inclined baffle surface extending from a point above the surface level of the chamber downwardly to the point of discharge of the nozzle.

5. In a photographic print washer, the combination with a container comprising two adjacently arranged treating chambers having a common center wall between them, the top of which wall is below the normal surface level of the chambers, of a baffle member in each chamber providing a baffle surface extending from above the surface level downwardly into spaced relationship with the center wall and a nozzle supported on said center wall and adapted to direct a stream downwardly along the same into each chamber.

6. In a photographic print washer, the combination with a container comprising two adjacently arranged treating chambers having a common center wall between them, the top of which wall is below the normal surface level of the chambers, of a baffle plate in each chamber extending from above the surface level downwardly into spaced relationship with the center wall, said baffle plates forming an overflow chamber between them and a nozzle supported on said center wall and adapted to direct a stream downwardly along the same into each chamber.

7. In a photographic print washer, the

combination with a treating chamber and an overflow chamber sealed from each other except for an intercommunicating passage between them below the overflow level, of

5 means for discharging a stream from the passage into the treating chamber, said passage being of sufficient size to permit a back-

flow therethrough into the overflow chamber and allow the incoming and outgoing streams to pass in close proximity.

JOHN A. ROBERTSON.
